UNITED STATES PATENT OFFICE.

FRANK A. COOK, OF HARTFORD, CONNECTICUT, ASSIGNEE TO UNDERWOOD TYPE-WRITER COMPANY, OF NEW YORK, N. Y., A CORPORATION OF NEW JERSEY.

TYPE-WRITING MACHINE.

1,063,858.

Specification of Letters Patent. Patented June 3, 1913.

Application filed February 24, 1910. Serial No. 545,567.

To all whom it may concern:

Be it known that I, FRANK A. COOK, a citizen of the United States, residing in Hartford, in the county of Hartford and State of Connecticut, have invented certain new and useful Improvements in Type-Writing Machines, of which the following is a specification.

This invention relates to paper deflectors for guiding paper around the platens of typewriting machines.

The main object of the invention is to provide simplified, improved and inexpensive means for accommodating and guiding accurately thick sheaves of sheets easily and efficiently as well as single sheets. For this purpose, the platen is provided with a paper deflector supported by rocking arms. The rear edge of the deflector underlaps the lower edge of the paper shelf and its forward edge extends past the usual forward feed rolls. The deflector is held against the under face of the platen by springs, and is withdrawn from the platen simultaneously with the pressure rolls. The arms guide the deflector about vertically toward and from the platen.

In the accompanying drawings, Figure 1 is a plan view showing the under side of a platen frame of the Underwood writing machine, equipped with my invention. Fig. 2 is a detail perspective view showing the manner of supporting the paper deflector. Fig. 3 is a sectional view showing the mechanism in normal position, parts being omitted to better disclose the invention. Fig. 4 is a similar view showing the rolls and deflector cast off. Fig. 5 is a fragmentary detail front view, showing the tension device for pressing the rolls against the platen.

The cylindrical platen 1 has an axle 2 by which it is journaled in the ends 3, 4, of a platen frame. Said ends are connected by a fixed or rigid rear paper shelf 5 inclining downwardly and forwardly to the under part of the platen. Also rigidly connecting said ends is a tie rod 6, and hinged upon said rod is a pair of forwardly extending arms 7, carrying an axle 8, extending horizontally along the under side of the platen. On this axle is mounted a series of forward pressure rolls 9. Extending rearwardly from the rod 6 is a pair of arms 10 carrying an axle 11 upon which are rear pressure rolls 12. Springs 12a hold the forward

and rear pressure rolls against the platen. The roll-carrying devices are duplicated at the ends of the platen. By depressing a key 13, the pressure rolls are cast off or released from the platen, said key being connected by a link 14 to a crank 15 on a cam-shaft 16 engaging lugs 17 connected with the arms 7, 10, supporting the pressure rolls. Along the bottom edge of the paper shelf 5 are formed paper guiding tongues 18 projecting forwardly and downwardly through openings 19 formed in a yielding paper deflector or apron 20 lying beneath and conforming generally to the curvature of the platen 1, and having along its rear edge a strengthening bead 20a. Said paper deflector 20 is supported by depending ears 21 pivotally connected at 22, to the free ends of arms 23 journaled at 24, to swing on the rod 6 so that the deflector may move about vertically from and toward the platen. Removable caps 24a on the arms permit them to be disengaged from the tie rod 6. The arms 23 may swing independently of each other, to permit either end of the deflector 20 to swing from the platen. This affords a yielding and perfect fit of the deflector to the platen or the paper thereon under all conditions.

The paper deflector near its rear edge 85 has openings 25 up through which the rear pressure rolls 12 project; and at its front edge, it is recessed at 26, for the front pressure rolls 9.

The free ends of long, flexible springs or yielding fingers 27 secured to the deflector intermediate its rear and forward edges at 28, rest upon the axle 8 of the releasable front pressure rolls to hold or press the ends of the deflector independently of each other upward against the platen. Hooks 29 on the front portion of the deflector catch under the front axle 8.

When the release key 13 is depressed, the cam-shaft 16 is rocked to swing the roll supporting arms 7, 10, in the usual manner, to release the rolls. The throw of the front axle 8 away from the platen brings the axle against the hooks 29, to carry the deflector away from the platen; the arms 23 rocking downwardly on the rod 6 until arrested by the engagement of their stops 30 with the cam-shaft 6, which also arrests the deflector. The deflector may move down in a similar manner to accommodate a thick sheaf of 110

sheets inserted between the platen and the deflector. The deflector 20 is securely held by means of the rocking arms 23, while it is permitted to adjust itself accurately to the curve of the platen or of the sheets thereon.

It will be observed that the fingers 18 projecting from the lower edge of the paper shelf 5 guide the sheets into the bite of the 10 rear pressure rolls 12, the fingers yielding to accommodate thick piles of sheets.

The paper shelf may be placed in any desired or usual position relatively to the platen.

15 Having thus described my invention, I claim:

1. In a typewriting machine, the combination with a platen, feed roll shafts carrying feed rolls and a release key to cast off 20 the rolls, of a paper deflector beneath the platen, and having a hinged connection with the platen frame, a yielding support to press the deflector against the platen, and a device on the paper deflector catching over 25 one of the roll carrying shafts to be moved thereby when the rolls are cast off, to release the deflector from the platen.

2. In a typewriting machine, the combination with a platen frame, and paper feed 30 roll devices, of a paper deflector extending along the platen, arms journaled upon the platen frame and pivotally connected to the deflector, a yielding device to press the deflector against the platen, and a releasable 35 pressure roll having a shaft which supports said yielding device.

3. In a typewriting machine, the combination with a cylindrical platen and a platen frame, of a paper guide or deflector curving 40 around the under side of the platen and extending substantially from end to end thereof, independently movable arms pivoted upon the platen frame, said deflector pivoted at its ends to said arms, so that either 45 end of the deflector may yield, a releasable pressure roll shaft, and yielding devices supported by said shaft for independently pressing the ends of the deflector against the platen.

50 4. In a typewriting machine, the combination of a cylindrical platen and a platen frame, a paper shelf having its lower edge adjacent to the said platen, a curved deflector, pivotal supports for said deflector 55 adjacent the lower edge of said paper shelf, a spring normally tending to press said deflector against said platen, feed rollers normally engaging said platen and connected with said deflector so as to hold said deflector normally against said platen, and

means for casting off said rollers and said deflector and holding them removed from said platen.

5. In a typewriting machine, the combination of a platen, a platen frame, a pair 65 of pivoted arms arranged transversely under said platen, a deflector pivotally attached to said arms, roller arms also mounted transversely under said platen, feed rollers mounted on said roller arms, a spring for pressing said deflector against said platen when said rollers are pressed against said platen, and means for casting off said rollers and said deflector.

6. In a typewriting machine, the combination with a platen and platen frame, of a paper table on said frame, fingers extending from said table against which a deflector may lie, a pivoted arm holding said deflector operatively related to said table, 80 a pressure roll having a casting off mechanism, and means for moving one edge of said deflector with said roll.

7. In a typewriting machine, the combination with a platen and platen frame, of a 85 paper table on said frame, a deflector onto which paper is guided from said table, a pressure roll, casting off means therefor, an arm on said deflector swinging it with said roll, and a spring resting on the axle of said 90 roll tending to move the deflector against the platen.

8. In a typewriting machine, the combination with a platen frame, paper feed roll devices, and casting off mechanism therefor, 95 of a paper deflector having ears, a paper table engaging said deflector, arms journaled on the platen frame and pivotally connected to the ears to permit a bodily movement of said deflector with reference 100 to said paper table, yielding means to press the deflector against the platen, and a positive connection between the deflector and the casting off mechanism to release the deflector from the platen.

105 9. In a typewriting machine, the combination with a platen frame, a platen and a deflector extending therealong, of a paper table engaging said deflector, arms pivotally connected to the deflector and to the platen 110 frame, a spring to press the deflector against the platen, and a releasable pressure roll having a shaft to support said spring and move said deflector positively to and from the platen.

FRANK A. COOK.
